PULVERIZER FOR PILLS, TABLETS AND THE LIKE

Ezra C. Bull, 815 Cleveland St., Durham, N.C.

Filed Mar. 1, 1963, Ser. No. 73,779

Term of patent 14 years

(Cl. D16—3)

FIG. 1

FIG. 2

FIG. 3

I claim:

The ornamental design for a pulverizer for pills, tablets and the like, substantially as shown.
